UNITED STATES PATENT OFFICE.

JOHN M. MILLS, OF TISKILWA, ILLINOIS.

CURTAIN-FIXTURE.

No. 822,009.

Specification of Letters Patent.

Patented May 29, 1906.

Application filed July 15, 1905. Serial No. 269,876.

To all whom it may concern.

Be it known that I, JOHN M. MILLS, a citizen of the United States, residing at Tiskilwa, in the county of Bureau and State of Illinois, 5 have invented certain new and useful Improvements in Curtain-Fixtures, of which the following is a specification:

This invention relates to an improved support for shade rollers or curtains, and has for 10 its object to produce a device of this character which will be very effective in operation and which can be formed out of a simple piece of metal.

A further object is to produce a bracket 15 which can be easily and quickly placed in position without the use of tools, which will be neat in appearance, and which will not mar the window-casing to any appreciable extent.

For a full description of the invention and 20 the merits thereof and also to acquire a knowledge of the details of construction of the means for effecting the result reference is to be had to the following description and accompanying drawings, in which—

25 Figure 1 is a plan view of the device. Fig. 2 is a side view of a bracket formed with an eye. Fig. 3 is a similar view of a bracket formed with a hook. Fig. 4 is a detail perspective view of the device.

30 Corresponding and like parts are referred to in the following description and indicated in all the views of the drawings by the same reference characters.

The numeral 1 designates the shank of the 35 bracket, which is threaded at one end, as seen at 2, to enable it to be secured in position and is provided at its opposite end with means for supporting the shade-roller. The shank 1 is bent outward to form a shoulder 3, which 40 is approximately at right angles to the threaded portion and serves as a stop to prevent the bracket from being screwed too far into the casing and also throws the major portion of the bracket at an angle to the plane of the 45 supporting end, and therefore out of engagement with the shade-roller. The end of one of these brackets is bent around to form an eye 4 for the reception of the round bearing at one end of the shade-roller, while the end 50 of the opposite bracket is bent so as to form

a hook 5 to receive the flat stud on the other end of the roller. A lug or keeper 6 is formed at the mouth of the hook 5 by cutting into and bending a portion of the metal out on the side adjacent the shank. Particular attention is called to the fact that the bend in the shank 1 serves the double function of forming the offset, which engages the face of the casing and prevents the bracket from being screwed in too far, and also serves to eliminate all undue friction by throwing the major portion of the shank away from engagement with the shade-roller. 55

It will be readily seen that while these brackets as designed by me can be very 60 cheaply manufactured from wire or similar material they possess all the advantages of more complicated and more expensive devices, in that they form a perfect support for the shade-roller and can be quickly and easily 65 placed in position without marring the window-casing to an appreciable extent. 70

Having thus described the invention, what is claimed as new is—

As a new article of manufacture, a curtain- 75 fixture or supporting-bracket comprising a shank consisting of a single length of wire or like material threaded at one end so as to be screwed into a support, said shank being projected laterally at a point between its ends to 80 form a horizontal offset portion or shoulder adapted to limit the penetration of the threaded portion aforesaid, the outer portion of the shank extending outwardly from the outer end of the shoulder and at an angle to 85 the axis of the threaded portion above mentioned, the outer extremity of the angularly-arranged portion of the shank being bent to form a member for supporting a curtain- 90 roller, said supporting member being arranged in a plane at approximately a right angle to the plane including the offset and threaded portions of the shank.

In testimony whereof I affix my signature in presence of two witnesses.

JOHN M. MILLS. [L. S.]
